DUAL PLATEN AND TYPE BARS THEREFOR

Albert C. Buehler, Kenilworth, Ill., assignor to
Victor Adding Machine Company, Chicago, Ill.,
a corporation of Delaware

Application June 14, 1934, Serial No. 730,603

22 Claims. (CL. 197—22)

The invention relates to a printing mechanism adapted for use in connection with an adding machine and more particularly of a type wherein a double platen is employed and which has a plurality of printing elements arranged in pairs to coat simultaneously with each of the platens for making original duplicate impressions on sheets placed thereon.

In various types of entries wherein the serial number, quantity, total amount, cost, etc. are to be made, it is often found desirable to make a complete entry on one of the sheets and only a partial entry on another, such as for example the total amount and the cost.

Heretofore, to produce an entry as above described, it was necessary to make two originals which required two set-ups of the machine. It is the purpose of this invention to simultaneously print original entries without the necessity of duplicating the work or making two originals one after the other, or to print one of the sheets with a complete record thereon while the other sheet receives only a portion of the record.

The chief objects of the invention are the provision of a plurality of platens, each having a plurality of printing elements coating therewith which are selected in pairs by means of the usual depressible keys and are actuated to position them in the printing line by means of an actuator common in adding machine construction.

A further object is the provision of a plurality of platens arranged for longitudinal movements with and independently of each other and being each provided with a paper table for guiding a sheet of paper therearound upon which simultaneous impressions may be made at various places thereon.

A still further object is the provision of carriage means enabling the platens to be carried in parallel relation with each other to receive the impact of the respective type bars coating therewith, and having spacing means regulating the longitudinal positioning of the platens with respect to each other to align them with respect to the desired position at which the impressions are to be made, and having means for bodily adjusting the platens while retained in position with respect to each other.

And a still further object is the provision of a plurality of platens each being guided for independent movements on a main carriage and for a rockable swinging movement on the main carriage to render them visible during the insertion of paper to be printed.

55 Referring to the drawings:—

Figure 1 is a medial longitudinal sectional view illustrating a plurality of platens each receiving the impact of type bars coating therewith.

Figure 2 is a face view of the platens taken on the line 2—2 of Fig. 1.

Figure 3 is an end elevation of the platens and carriage therefor and also illustrating a portion of the adding machine.

Figure 4 is a detail partial rear elevation of the main carriage locking means forming the normal centering means therefor and the adjustable engageable members coating therewith.

Figure 5 is an end elevation of the carriage illustrating the driving means for the platens carried thereon.

Figure 6 is a detail sectional view taken on the line 6—6 of Fig. 5.

Figure 7 is an enlarged detail perspective view of the spring retaining means for the carriages.

Figure 8 is a view in reduced size of two sheets which have been simultaneously printed with a full record on one of the sheets and a partial record on the other sheet; and

Figure 9 is a view in reduced size of two sheets similar to Fig. 8 wherein a full record has been made on a vertical line on one of them, and in a horizontal line on the other.

Reference numeral 10 designates the keys of the adding machine adapted to be depressed and having the stems 11 extending through and suitably guided in a keyboard 12 so that the lower ends of the stems 11 will coat with a rack bar 13 when depressed. The rack bar 13 carries a link 14 which is also pivotally attached at 15 to a bell-crank 16 which is mounted for rocking movements on a transversely extending shaft 17 connected to the actuating mechanism (not shown), by means of a link 18 which is pivotally connected at 19 to a downwardly extending ear 20 of the bell-crank 16.

The link 18 is provided with an elongated slot opening 18a through which a pin 21 extends being secured to a companion link 22 slidably mounted adjacent the link 18. The link 22 is connected for movement with the link 18 by means of a tension spring 23 fixed to the pin 21 and to a pin 24 on the link 18 providing a yieldable connection therewith when the actuating mechanism is operated and the bell-crank 16 is withheld from movement by means of the link 14 and the rack bar 13 which is withheld by means of a keyboard lock mechanism common in adding machine construction (not shown).

The bell-crank 16 is also connected at 25 to a vertically disposed slide member 26 provided

with elongated slot openings 26a and 26b for sliding movements on a pair of transversely extending guide members 27 and 28. The vertically disposed slide member 26 is connected to a pair of rockable type bars 29 and 30 respectively by means of a pair of links 31 and 32 which are pivotally connected to the member 26 at 33 and 34 and to the type bars 29 and 30 at 35 and 36. The type bars 29 and 30 are pivotally connected at 37 and 38 to a pair of links 39 and 40 respectively which are pivotally supported on the shafts 41 and 42 and with the companion links 31 and 32 support the type bars 29 and 30 on floating centers 35-37 and 36-38.

The links 39 and 40 are provided with extensions 43 and 44 respectively, adapted to be engaged by means of the extensions 45 and 46 of a member 47 carried for sliding movements on a transversely extending shaft 48 by means of a slot opening 49 therein forming a tripping mechanism for the links 39 and 40. The lower end of the member 47 is pivotally connected at 50 to a rocker arm 51 carried on a transversely extending shaft 52 and has its free end portion 53 normally engaged by an ear 54 of the vertically disposed slide member 26. The member 47 is normally retained in raised position by means of a tension spring 55 secured to a shaft 56 and to the rocker arm 51 which normally retains the extensions 45 and 46 of this member 47 into the path of the extensions 43 and 44 of the links 39 and 40, thereby retaining these links in a fixed locked position for the rocking movements of the type bars 29 and 30 thereon when the vertically disposed slide member 26 is moved by means of the bell-crank 16.

The links 39 and 40 are urged to rock in a rearward direction on their shafts 41 and 42 by means of the tension springs 57 and 58 fixed thereto and to the shaft 28 and 59 which normally tend to throw the type bars rearwardly as the extensions 45 and 46 of the member 47 are withdrawn from engagement with the extensions 43 and 44 of the links 39 and 40.

Both of the links 39 and 40 are provided with outwardly extending integral portions 60 and 61 respectively adapted to be engaged by the pins 62 and 63 carried on relatively short arms 64 and 65 which are pivotally mounted on the shafts 41 and 42. These arms 64 and 65 are connected together by means of a link 66 and are arranged for movement by means of a depending link 67 connected to the pin 62 with its lower end portion pivoted at 68 to a bell-crank 69 supported on a shaft 70 and with the other leg connected to the actuating mechanism (not shown), by means of a link 71.

Each pair of type bars 29 and 30 is arranged and connected to be operated by the actuating mechanism in the manner as above described, and it is thought that a description of one will suffice for a description of all.

The link 67 has a finger 72 pivotally connected thereto at 73 and normally urged upwardly by means of a compression spring 74 and is limited in its upward movement by means of an ear 75 on the link 67. This finger 72 is positioned a sufficient distance below the rocker arm 51 so as to permit of a free movement therebetween as the link 67 is moved upwardly by means of the bell-crank 69 and the connecting link 71 under the control of the actuating mechanism (not shown).

The purpose of the free movement between the finger 72 and the rocker arm 51 is to permit of the disengagement of the pins 62 and 63 with

the extensions 60 and 61 of the links 39 and 40. The connecting link 71 operating the release of the pins 62 and 63 with the extensions 60 and 61 is connected with the actuating mechanism so as to be moved subsequent to the movement of the links 18 and 22 actuating the bell-crank 16 for positioning the vertically disposed slide 26 and the type bars 29 and 30 connected thereto by means of the links 31 and 32 in the printing line. These type bars 29 and 30 coat with a pair of platens 77 and 78 which are normally positioned in the printing line. As the actuating mechanism is operated a greater distance upon its normal movement, the finger 72 carried on the link 67 will engage the end 53 of the rocker arm 51 and force the same upwardly when the ear 54 of the vertically disposed slide member 26 is out of engagement therewith and permit of a rocking movement of the arm 51 on the shaft 52 and cause a downward pull on the member 47 against the tension of the spring 55 and release the extensions 45 and 46 thereof from the extensions 43 and 44 of the links 40 permitting them to be urged rearwardly by means of the tension springs 57 and 58 and carrying the type bars 29 and 30 therewith for an impact against the platens 77 and 78.

The type bars 29 and 30 are selected in the usual manner by means of the keys 10 and are positioned in the printing line by means of their engagement with the rack 13 and as the machine is operated, the following sequential movements must occur: the selected type bars 29 and 30 are first positioned in the printing line and then the pins 62 and 63 are moved out of engagement with the extensions 60 and 61 of the links 39 and 40. Then the finger 72 carried on the link 67 which actuates the release of the pins 62 and 63 carries this finger 72 into engagement with the rocker arm 51 and upon a further movement, will raise the same upwardly causing the member 47 to be drawn downwardly to cause the extensions 45 and 46 thereof to be drawn out of the path of the extensions 43 and 44 of the links 39 and 40 and cause them to be rocked rearwardly by means of the tension springs 57 and 58 for an impact of the type bars 29 and 30 against the platens 77 and 78.

The type bars 29 and 30 are withdrawn from the platens 77 and 78 before being restored to their normal positions by means of the links 39 and 40 which are caused to be moved by a forward rocking movement of the links 39 and 40 caused by the engagement of the pins 62 and 63 with the extensions 60 and 61 thereof and at which time the finger 72 will be free of the rocker arm 51 and release the member 47 to be urged upwardly by means of the spring 55 until the extensions 45 and 46 thereof engage the extensions 43 and 44 of the links 39 and 40 retaining them in normal locked position.

The type bars 29 and 30 are operated by means of a vertically disposed slide member 26 which has an ear 54 overlying the end 53 of the rocker arm 51 so that as the corresponding finger 72 is moved into engagement with the arm 51, the same will be withheld from movement by means of its contact with the ear 54. This ear 54 forms a safety lock for the tripping mechanism 47 to prevent the type bars 29 and 30 from being moved for an impact against the platens 77 and 78 in those banks where the keys 10 have not been depressed. When the rocker arm 51 is withheld against the ear 54 upon the operation of the machine, the finger 72 on the link 67 will abut this

arm 51 and will yield against the tension of the torsion spring 74 on the pivot 73 and permit of a further upward movement of the links 67 without effecting a rocking movement of the rocker arm 5 and the release of the member 47 to release the links 89 and 40 in that particular bank.

The platens 77 and 78 are carried in spaced relation with the type bars 29 and 30 supported on the platen shafts 79 and 80 respectively, and 10 are carried in carriages 81 and 82 which are provided with pairs of rails 83 and 84 respectively coacting with pairs of rails 85 and 86 to form ball races for the carriages 81 and 82. The rails 85 and 86 are fixed to U-shaped end plates or 15 frame members 87 and 88 which are pivotally mounted at 89 and 90 to the side frames 91 and 92 of a main carriage 93. The main carriage 93 is provided with a pair of rails 94 which provide for a longitudinal movement thereof on the tracks 20 95 and 96.

The platens 77 and 78 are arranged for independent longitudinal sliding movements on their platen shafts 79 and 80 in their carriages 81 and 82 and are retained in fixed adjusted position 25 by means of the springs 97 fixed to the carriages 81 and 82, having their free end portions 97a overhanging the rear rails 85 and 86 respectively. The springs 97 are identical and are of a T-shape formation, the shank 98 of which is provided with the openings 99 through which the screws 100 extend to secure the same to the carriages. The free end portion 97a of the spring 97 is provided with a depression 101 adapted to 30 coact with serrated edges 102 and 103 on each of the rearwardly disposed rails 85 and 86 guiding the carriages 81 and 82, and forming retaining means to releasably secure these carriages 81 and 82 of each of the platens 77 and 78 in fixed adjusted position with respect to a longitudinal 35 sliding movement independently of the main carriage 93.

The platens 77 and 78 are each provided with a paper table 104 fixed to and carried with the carriages 81 and 82 and extending upwardly at an 40 angle to the rear of these platens and having its forward ends 105 terminating into lips 105a formed to conform to the contour of the platen to guide the paper fed therearound outwardly to the rear of the machine. A guard 106 is 45 arranged in spaced relation with each of the paper tables 104 for directing the inserted paper therebetween to the platen rolls to be gripped by means of the feed rollers 107 carried by the paper tables 104 and coacting with the platens 77 and 78. A 50 paper rest 108 is also carried on each of the carriages 81 and 82 to support the paper to guide the same outwardly of the machine.

The platen shafts 79 and 80 are preferably of 55 square stock providing a key for the turning movements of each of the platens while permitting them to slide longitudinally on these shafts which are journaled in the frame members 87 and 88 and have the twirler-knobs 109—109 fixed thereto outwardly on one side of the main carriage 93 and the twirler-knobs 110—110 keyed to the other 60 ends of these platen shafts 79 and 80 and arranged for sliding movements thereon. These twirler-knobs 109 and 110 provide means for line-adjusting each of the platens 77 and 78 at whatever position they may be on their respective 65 platen shafts 79 and 80.

The twirler-knobs 110 are provided with hubs 111 which loosely carry sprocket-wheels 112 and 113 around which a chain 114 extends connecting 70 the two for simultaneously driving them. In-

tegral with each of the sprocket-wheels 112 and 113 are clutch teeth 115 and 116 which are normally engaged by the respective clutch members 117 formed on the inner end portion of the hubs 111 of the twirler-knobs 110 carried on the platen shafts 79 and 80. These clutch members 117 are each provided with toothed portions 118 adapted to engage the clutch teeth 115 and 116 of the sprocket-wheels 112 and 113 for a driving connection therewith in either direction of their movement being controlled for engagement and disengagement to manually adjust the platens for horizontally aligned printing. The hubs of the sprockets 112 and 113 are provided with annular grooves 119 and 120 into which the ends 121 of 15 L-shaped members 122 extend. These L-shaped members 122 are secured to the frame member 88 and retain the sprocket-wheels 112 and 113 in aligned position with respect to each other. To retain the clutch members 117 in either a clutched 20 or declutched position, I provide the depressed portion 123 formed from the L-shaped brackets 122 which are provided with a V-portion 124 that normally extends into the annular groove 125 of each of the clutch members 117. These 25 depressed portions 123 provide a yielding tension in the grooves 125 of the clutch members 117 and permit of an easy release thereof by merely forcing the twirler-knobs 110 inwardly which will cause these depressed portions 123 to yield and 30 retain the clutch members out of engagement with the clutch teeth 115 and 116 of the sprocket-wheels 112 and 113.

The manual rotary adjustment of these platen shafts 79 and 80 by means of the twirler-knobs 35 109 and 110 is for the purpose of adjusting the platens independently of their mechanical feed means which will be presently described.

Adjacent the sprocket-wheel 112 and integral therewith is a ratchet-wheel 126 which receives 40 its driving power by means of a dog 127 pivotally carried on an arm 128 at 129 and which is movable with a rockable member 130 that is pivoted in the side frames 91 and 92 by means of the trunnions 131. The pawl 127 is normally 45 urged into engagement with the ratchet-wheel 126 by means of a tension spring 132 connected thereto and to the arm 128. An L-shaped arm 133 is pivotally mounted on the trunnion 131 adjacent the arm 128 and is provided with a pin 50 134 adapted to extend outwardly of the arm 128 and which may be positioned into the path of the pawl 127 upon its movement to render the pawl ineffective with the ratchet-wheel 126. A quadrant 135 is secured to the side frame 92 of 55 the carriage 93 and retains the L-shaped arm 133 with the pin 134 thereof into or out of the path of the pawl 127.

The rockable member 130 overlies a push-rod 136 which extends upwardly about midway of the 60 length of the carriage 93 and which is connected for movement with the actuating mechanism upon the reverse movement of the actuator shaft for causing a rocking movement of the rockable member and a step by step feed of the pawl 65 127 with the ratchet-wheel 126 and the upper platen shaft 80 will be turned thereby by means of the chain 114 and the clutches 115—118 and 116—118.

It is often found desirable to make several 70 horizontally aligned impressions on these platens 77 and 78 and when this condition occurs, the clutch members 118 may be disengaged from their respective clutch members 115 and 116 by means of pressing in the twirler-knobs 110 which renders 75

the ratchet-wheel 126 free of its driving movements with the shaft 79 and the pawl 127 freely turns the ratchet-wheel when in engagement therewith.

As thus far described, the device provides for a main carriage 93 having separate and independently movable carriages 81 and 82 carried thereby which have the platens 77 and 78 carried thereon. These carriages 81 and 82 permit of longitudinal sliding movements of the plates independently of each other and are each provided with yieldable spring means 97 for withholding them in their longitudinally adjusted positions and readily releasable for longitudinal adjustments at the will of the operator.

The platens 77 and 78 are also provided with feed means for automatic line spacing by means of the feed pawl 127 carried on the arm 128 fixed to the movable member 130 and operable by the push-rod 136 connected to the operating mechanism and which may be rendered inoperative at the will of the operator by means of manually moving the L-shaped arm 133 to cause the pin 134 thereof to be positioned into the path of the pawl 127 and withhold the same from engagement with the ratchet-wheel 126.

It will be noted that the platens 77 and 78 are carried bodily on the frame members 87 and 88 which are mounted for swinging movements on the side frames 91 and 92 of the main carriage 93 at 89 and 90 which permits the operator to bodily swing the platens 77 and 78 as a unit with the frame members 87 and 88 on these pivots 89 and 90 to substantially a horizontal position (dotted lines Fig. 3), to permit of visibility while aligning and adjusting the paper inserted in the desired position to be printed. The frame members 87 and 88 support a transversely extending shaft 137 which carries an L-shaped arm 138 on each end thereof which is provided with a finger grip 139 which coacts with a fixed finger grip 140 formed outwardly of the frame members 87 and 88. The free end 141 of the arm 138 is provided with an extension 142 adapted to normally engage a notched-out portion 143 in the bosses 144 of the side frames 91 and 92 for locking and withholding the platens in their normal position and aligned in printing relation with the type bars 29 and 30. Each of the ends 142 of the arms 138 is also adapted to engage a notched-out portion 145 positioned at approximately 90° of the notch 143 in the side frames 91 and 92. These arms 138 are normally urged with the ends 142 thereof in the notch 143 of the boss 144 by means of a tension spring 146 fixed to the arm 138 and to a pin 147 fixed in the frame member 87. After the platens 77 and 78 are adjusted longitudinally on their platen shafts 79 and 80 respectively, the line-spacing may be had by manually turning the twirler-knobs 109 and 110 and during the operation of the machine, a step by step rotary feed of each of the platens will be had which forms automatic line-spacing means during the printing operations of the machine while the pawl 127 is in operative relation with the ratchet-wheel 126.

It is sometimes found desirable to bodily carry the platens 77 and 78 while they are in their adjusted positions and in order to do so, I provide a normal centering means designated as a whole as 148 which comprises a pair of inwardly directed opposed arms 149 and 150 supported on the bolts 151 and 152 secured to an upwardly extending flange 153 of the adding machine.

The arms 149 and 150 are provided with the pins

154 and 155 respectively adapted to extend through the openings 156 and 157 in the flange 153 and are connected together by means of a tension spring 158 which exerts a tension on the arms 149 and 150 to hold them in raised position with the pins 154 and 155 in engagement with the top edge of the respective openings 156 and 157. Each of the arms 149 and 150 are provided with relieved portions 159 and 160 which form a space 161 therebetween to receive the ends 162 of adjustable engageable members designated as a whole as 163 and which are carried on a square shaft 164 journaled for rocking movements in the side frames 91 and 92 of the main carriage 93. The adjustable members 163 are formed to snugly fit the square shaft 164 and are arranged for sliding movements thereon to adjust the same at any desired position.

The members 163 are each provided with outwardly extending ends 162 which have a stud 165 fixed thereto and adapted to extend upwardly through a flange 166 which is provided with a cam member 167 pivoted to the stud 165 by means of a pin 168 and which is provided with a finger grip 169 for manually adjusting the same. When the members 163 are properly positioned and clamped by means of the cam 167 to the square shaft 164, and the main carriage 93 is moved in one direction or the other engaging either the arms 149 or 150, the same will be caused to yield against the tension of the spring 158 while the other arm which is not being engaged remains in position forming an abutment against which the end 162 of the member 163 abuts, forming a permanent stop therefor at which time the arm 162 that has been depressed will be urged upwardly by means of the spring 158, and lock the extension 162 in the space 161 provided by the notched-out portions 159 and 160 of these arms 149 and 150 while in their normal positions.

In order to release the main carriage 93 for longitudinal sliding movements, I provide an arm 170 fixed to each end of the square shaft 164 outwardly of the side frames 91 and 92. Each of the arms 170 is provided with a finger piece 171 and is retained in a normal raised position by means of a tension spring 172 fixed thereto and to a pin 173 fixed in the side frames 91 and 92. The finger piece 171 serves to manually rock the shaft 164 and raise the extension 162 of the member 163 clamped thereto out of engagement with the opening 161 formed by the arms 149 and 150 at which time the carriage will be free to be moved until again engaged by the extension 162 of the next member 163 in the same manner as above described, and the distance which the main carriage 93 is permitted to move, depends upon the positioning of these members 163 on the square shaft 164.

A ribbon 176 and 177 is arranged in each of the printing lines between the platen 77 and the type bars 29 and between the platen 78 and the type bars 30. These ribbons 176 and 177 are arranged for a feed during the operating movements of the machine and the mechanism therefor is not shown in the drawings as any type of ribbon feed may be employed.

Each of the platens 77 and 78 may be individually adjusted by means of declutching the same at 115 and 116 so that either of the platens 77 or 78 may be rendered inoperative with the driving mechanism or one or the other may be individually driven as in the case where vertically aligned printing on one sheet and horizontally aligned printing on the other sheet is desired.

These printing operations may be had simultaneously in one set-up of the machine and the platen which is not being fed mechanically may be moved manually by means of the finger grips 174—174 5 or 175—175 of either of the carriages 81 and 82.

The facsimiles shown in Figs. 8 and 9 illustrate the results which may be had with the dual type of platens and coacting type bars therefor. In Fig. 8, the printing is shown in a vertical line on the top sheet such as under the heading "Serial number" the number 272 appears, under "Quantity" the number 21 appears, under "Total" 169 appears, and under "Cost" the amount of 280.10 appears. On the second line of the top sheet the numbers 140, 18, 120 and the cost 116.00 appear, and directly below and corresponding with the serial number, quantity, total and cost. All of the numbers are inserted in a vertical line below the totals under which they are to be positioned, while on the companion sheet which is printed at the same time, the total 169 and the cost 280.10 appear in a vertical line and the total 120 and cost 116.00 are in the next space and also in a vertical line, or in the other words, the totals and the costs are in horizontal alignment in the lower sheet and the total amount of 396.10 appears at the right-hand edge of the sheet, while in the top sheet the same amount appears vertically aligned in the cost column. This is accomplished by means of a step by step feed mechanism of the platen being fed by the dog 127 engaging the ratchet-wheel 126 and driving the upper platen 18 while the lower platen 17 is disengaged from the feeding mechanism and is being moved manually longitudinally of the main carriage 93 by means of the finger grips 175 of the carriage 81 and the platens having been positioned with respect to each other at the start of the operation so that the lower platen was clear of the type bars 29 at the time the serial numbers and the quantity numbers were inserted in the top sheet.

In Fig. 9 a full record is shown on both of the sheets with the imprinting in a vertical line on the top sheet and in a horizontal line on the lower sheet.

These facsimiles only indicate various types of printing for the purpose of illustrating the kind of work which may be accomplished with a machine of this type, but many other combinations may be arranged.

With a means as above described for clutching and declutching the individual platens with respect to the automatic driving mechanism for line-spacing them as the machine is being operated, each of the platens may be operated independently of one another under the control of the driving mechanism or both of them may be operated as in the case of printing a line of figures on both sheets and all in vertical alignment. Either of the carriages may be adjusted longitudinally so as to print at the desired position on the paper. In addition to the individual longitudinal adjustments of the platens, they may also be adjusted bodily by means of the main carriage 93.

I contemplate as being included in these improvements all such changes, variations and departures from what is thus specifically illustrated and described as fall within the scope of the appended claims.

I claim:—

1. In a device of the character described, the combination with a pair of platens arranged in superposed relation one with the other and type carrying elements coacting therewith, of means

whereby said platens may be adjusted longitudinally with respect to each other, and means whereby said platens may be bodily carried independently of said longitudinal adjustment.

2. In a machine of the character described, the combination with a plurality of platens and type carrying elements coacting therewith, of means for causing a step by step rotary movement of the platens, said platens being carried for longitudinal movements with respect to each other, means releasably holding the platens in adjusted longitudinal positions, and means whereby said platens may be bodily carried while in their adjusted positions.

3. In combination with an adding machine having a duplicate set of type carrying elements, a main carriage, platens arranged on the main carriage adapted to receive the impressions of said type carrying elements, means for adjusting and retaining the platens on the main carriage in printing relation with the type carrying elements, and means controlling a step by step rotary movement of the platens while in their adjusted positions.

4. In a key-set adding machine having type carrying type bars arranged in sets and an operating mechanism therefor, a main carriage, platens carried on the main carriage and adapted to receive the impressions of the selected type of the type bars, said platens being carried for independent movements and for movements with each other on the main carriage, and line-spacing means operatively connecting the platens and arranged with the operating mechanism for a step by step rotary movement of the platens. 35

5. In a device of the character described, the combination with a main carriage, of a pair of platens arranged for longitudinal movements and in superposed relation one with the other on the main carriage, type carrying elements coacting with each of the platens, retaining means whereby said platens may be adjusted longitudinally with respect to each other, and adjustable means on said main carriage to determine the positions thereof while bodily carrying the platens as a unit 45 for longitudinal adjustments therewith.

6. In a machine of the character described, the combination with a main carriage, of a plurality of platens carried for longitudinal movements on the main carriage, a set of type carrying elements for each of the platens, yieldable means retaining the platens releasably positioned with respect to their longitudinal movements on the main carriage, line-spacing means operatively connecting each of the platens, and means for 55 rendering said line-spacing means ineffective with one or the other of the platens.

7. In a key-set adding machine having type carrying type bars arranged in sets, a main carriage, platens carried for independent movements 60 on the main carriage and adapted to be normally positioned in a printing line to receive the impressions of the selected type of the type bars, feed means associated with each of the platens for causing a rotary step by step feed thereof, 65 and manually manipulative means associated with the main carriage and the adding machine forming means for selectively positioning said main carriage for bodily carrying the platens therewith. 70

8. In combination with an adding machine having a duplicate set of type carrying elements, a main carriage, a platen for each set of type carrying elements, said platens being carried for longitudinal movements and for swinging movements 75

on said main carriage, said longitudinal movements permitting of independent adjustments of the carriages, while said swinging movements provide for the positioning of said platens to render visibility to the operator.

9. In combination with an adding machine having duplicate type carrying elements, a main carriage duplicate platens for said type carrying elements adapted to be individually moved longitudinally on the main carriage, line-spacing means operatively connecting said platens with the actuating mechanism of the adding machine, and lock means releasably securing the platens for a swinging movement on the main carriage providing visibility for the longitudinal adjustments of the platens.

10. The combination with a dual platen and type bars therefor, of a main carriage supporting said platens for individual longitudinal movements thereon, of line-spacing means for each of the platens, engageable means operatively connecting the platens with the line-spacing means, and means for rendering said line-spacing means ineffective while connected to said platens.

11. The combination with a main carriage, a plurality of platens supported on the main carriage in printing position with type bars adapted to coat therewith, said platens being movable for adjustments longitudinally of their axis, means retaining the platens in adjusted positions, line-spacing mechanism for the platens, and means whereby the main carriage and platens may be moved longitudinally as a unit while said platens are in their adjusted positions.

12. The combination with a plurality of platens supported in printing position and having key selected type carrying type bars coating therewith for simultaneously making a plurality of like impressions, said platens being selectively movable longitudinally to various longitudinal positions into and out of the path of the type bars, a main carriage bodily supporting the platens in their adjusted positions, and means coacting with the main carriage adapted to be selectively set to predetermine the longitudinal positioning thereof to position the platens to receive impressions at predetermined positioned thereon.

13. The combination with a plurality of platens supported in printing position in an adding machine and having key selected type carrying type bars coating therewith for simultaneously making like impressions thereon, said platens being movable longitudinally with respect to each other, a main carriage supporting the platens in printing position with the type bars, stop and retaining means on the machine, and adjustable means on the main carriage coacting with the stop and retaining means, said adjustable means being manually releasable from said stop and retaining means for permitting of longitudinal adjustments of the main carriage to predetermined positions on the machine.

14. The combination with a plurality of hingedly supported platens in printing position with a plurality of sets of type carrying type bars, said type bars being arranged for unitary movements for making like impressions on the platens, said platens being adjustable in a path to receive impressions of the type bars at various positions thereon, means retaining the platens in their adjusted positions, movable means bodily supporting the platens in their adjusted positions, lock means on the movable means retaining the same at predetermined positions for bodily adjusting the platens longitudinally with respect to

the type bars, and releasable lock means for bodily swinging the hingedly supported platens on their hinges to permit visibility thereto.

15. In a machine of the character described, the combination with a movable supporting frame having a plurality of independently slideable platens carried thereon, a set of type carrying type bars arranged for movement with each other and coacting with each of the platens for simultaneously making impressions thereon, and releasable controlled lock means on the supporting frame for bodily adjusting the longitudinal movements of the platens.

16. In a machine of the character described, the combination with a main carriage, a plurality of independently movable carriages supported on the main carriage, a platen carried on each of the independently movable carriages, a set of type bars being arranged in pairs for movement with each other and adapted to coat with each of the platens, releasable retaining means coacting with the carriages of each of the platens and permitting of their longitudinal adjustments, and manually controlled lock means for adjusting the main carriage to bodily adjust the platens with respect to the type bars.

17. In a machine of the character described, the combination with a main carriage supporting a plurality of independently movable carriages, a platen carried on each of the independently movable carriages and each having a set of type bars coacting therewith, said type bars being connected for simultaneous movements and for an impact with their respective platens, adjustable retaining means for the main carriage to bodily position the independently movable carriages and their platens with respect to each set of type bars, said independently movable carriages being also supported for a unitary swinging movement on the main carriage, and manually controlled lock and grip means for effecting a swinging movement of the movable carriages rendering the platens carried thereon visible to the operator.

18. The combination with a movable supporting frame having a carrying frame hingedly supported for swinging movements thereon, platens on the carrying frame, said platens being normally retained in printing position with a set of type carrying type bars that coat therewith, said platens being movable for independent adjustments on the carrying frame, and releasable lock means for releasing the carrying frame for a swinging movement thereof and said platens with respect to the movable supporting frame.

19. In an adding machine, the combination with a main carriage, of a plurality of independently movable carriages supported thereon, of platens carried on each of said independently movable carriages, a set of type bars for each of the platens, each being connected for movements one with the other for simultaneously imprinting like characters on each of the platens, and line-spacing means operatively connected with each of the platens for causing vertically aligned printing thereon.

20. The combination with a main carriage, of a plurality of platens supported for longitudinal movements with and independently of the main carriage, and a set of type carrying type bars coacting with each of the platens.

21. The combination with carriage means adapted to move in a path, of a pair of platens arranged one above the other and supported for

movements with and independently of the carriage means, and a set of type carrying type bars connected in pairs for simultaneous and duplicate impressions on each of the platens.

5 22. In combination with the carriage of an adding machine having a pair of platens carried for longitudinal adjustments thereon, said plat-

ens being arranged to swing bodily on the carriage providing visibility for their longitudinal adjustments, and lock means adapted to be controlled for securing the platens in operative and inoperative positions with respect to their swinging movements on the adding machine. 5

ALBERT C. BUEHLER.
